CLOTHES WRINGER

Thomas J. Little, Jr., Syracuse, N. Y., assignor to
 Easy Washing Machine Corporation, Syracuse,
 N. Y., a corporation of Delaware

Application September 15, 1937, Serial No. 164,018

2 Claims. (Cl. 68—274)

My invention relates to clothes wringers for washing machines.

An object of my invention is to provide a driving and reversing mechanism for a clothes wringer and a casing for said mechanism which may be built and assembled at a low cost.

Another object of my invention is to provide a standard casing for housing the driving and reversing mechanism of a clothes wringer wherein the casing is so constructed and arranged that it is adapted to receive and support interchangeably any one of a number of different wringer constructions.

Another object of my invention is to provide a casing for a clothes wringer in which the casing is made in two parts, split substantially at the center of the casing and preferably on a line parallel to the wringer rolls whereby the wringer driving and reversing mechanism may be conveniently assembled and the casing is particularly adapted to support the wringer rolls and the frame therefor.

My invention further contemplates the provision of a casing for the driving and reversing mechanism of a clothes wringer wherein means are provided for enabling the casing, together with the wringer rolls, to be swung about a vertical axis to position the wringer as desired with respect to the washing machine vat from which the wringer assembly is supported, said means including interengaging splines which may be readily disengaged to enable swinging movement of the wringer and which may be readily engaged to lock the wringer in the desired position.

Other objects and advantages of my invention will be more apparent from the following description when taken in connection with the accompanying drawing in which:

Figure 1 is a front elevation of the casing and wringer support of a clothes wringer and indicating in dotted lines the wringer rolls and the washing machine vat from which the wringer assembly is supported.

Figure 2 is a top plan view of the casing for housing the driving and reversing mechanism of the clothes wringer.

Figure 3 is a view taken on the line 3—3 of Figure 2 and showing one-half of the casing with the driving mechanism mounted therein.

Figure 4 is a view taken on the line 4—4 of Figure 3 showing the mechanism by which the wringer assembly is releasably locked in position.

Figure 5 is a view taken on the line 5—5 of Figure 3.

Figure 6 is a view of a part of Figure 3.

The clothes wringer casing of my invention, generally indicated by the numeral 11, is supported on a tubular column 12 which encloses a drive shaft 13 driven from the same source of power which operates the agitator or other washing element of the washing machine. The casing for housing the driving and reversing mechanism is formed in two parts 14 and 15 preferably split in equal halves along a plane 16 extending parallel to the wringer rolls, indicated in dotted lines and identified by the numeral 17. The casing might properly be termed a clam shell type of casing. A pair of dowels 18 serve to locate the halves of the casing with respect to each other to facilitate assembly of the casing, the halves of which are secured together by screws 19.

The driving and reversing mechanism comprises a driven bevel gear 21 and a pair of driving bevel gears 22 loosely mounted on a shaft 23. The lower end of the shaft 23 is provided with a pin 24 which engages in slots 26 formed at the upper end of the shaft 13. The complete wringer assembly through the pin and slot connection 24—26, by a vertical lift, may be readily removed from supporting tubular column 12.

A clutch element 27, fixed to but slidable along the shaft, is provided with clutch faces 28 adapted to be selectively engaged with cooperating clutch faces formed integrally with the bevel gears 22. The shaft 23 is constantly driven and, as is well known in the art, the clutch 27 is movable into driving engagement with one or the other of the bevel gears 22 to drive the wringer rolls in the desired direction.

The clutch element 27 is provided with a peripheral annular groove 29 in which is positioned a roller 31 secured to a crank arm 32. The crank arm 32 is eccentrically mounted on a shaft 33 which extends through an opening in the casing, half of which is formed in each half of the casing. The shaft 33 extends externally of the casing and has secured to the outer end thereof a suitable lever 34 adapted to provide a convenient handle by which the shaft 33 and crank arm 32 may be rotated to shift the position of the clutch 27 in one direction or the other.

In order that the clutch member 27, when in driving engagement with either one of the bevel gears 22, may be automatically returned to neutral position out of driving engagement when the pressure on the rolls 17 is released, I have provided the power transmission mechanism of the rolls with a control mechanism, generally indicated by the numeral 35, associated with the clutch operating shaft 33 and with the wringer 55.

release bar (not shown). The mechanism for stopping rotation of the rolls upon actuation of the pressure release bar of the wringer rolls constitutes no part of my invention and need not be more particularly described herein as any suitable mechanism for controlling the operation of the rolls upon actuation of the release bar may be mounted in the casing. The mechanism shown herein is generally similar to that shown in Geldhof Patent No. 2,072,632, issued March 2, 1937, the connection from the control mechanism to the pressure release mechanism of the wringer rolls being shown at 40.

Of particular importance in the wringer casing 15 of my invention is the ease with which the driving and reversing mechanism and the control elements therefor may be assembled in the casing. The shaft 23, together with the gears 22 and the clutch 27 mounted thereon, the gear 21 and the 20 control mechanism for the clutch 27 may be laid in one-half of the casing, and such parts of the mechanism which require pivot points or bearings in the casing, as indicated at 30, may be secured in position in said one-half of the casing and 25 then the other half of the casing bolted to the first half.

My novel casing structure has further advantages which are particularly important in the art 30 of clothes wringers for the reason that most manufacturers of washing machines do not make their own wringer and its supporting framework or housing. The wringer is usually manufactured as a standard unit by a wringer manufacturer who may supply several washing machine builders. 35 The wringer driving and reversing mechanism and its associated casing are, however, manufactured usually by the washing machine manufacturer who normally markets several price classes of washing machines, each of which is equipped 40 with a different wringer. It is, however, desirable that the casing for enclosing the driving and reversing mechanism be a standard unit adapted to support any one of a number of different styles 45 of wringers. The wringer casing of my invention is particularly adapted for this purpose.

A pair of lugs 35' is formed integral with each 50 half of the casing and a central bore 36 is formed in each of the lugs. When the halves of the casing are bolted together the bores 36 in the lugs are in alignment with each other and are 55 adapted to receive pins (not shown) from which the framework for the wringer rolls, indicated in dotted lines at 37, may be supported. Another lug 38, also provided with a central bore, is provided 60 in each half of the casing, the two bores being in alignment when the casing is in assembled condition. These bores are adapted to receive a pin (not shown) upon which is pivotally mounted a wringer shroud, indicated in dotted lines and 65 identified by the numeral 39. The shroud and its pivotal connection to the casing may be similar to that shown in my copending application Serial No. 155,664, filed July 26, 1937.

Each half of the casing has a depending portion 70 41 semi-circular in cross section which, when the two halves of the casing are secured together, form a depending hollow column 42 encircling the supporting column 12. The supporting column 12 extends upward and butts against a shoulder 75 of the casing, as indicated at 43. Ribs are formed internally of the two halves of the column 42, as indicated at 44, to strengthen the column and provide a bearing support on the supporting column 12. The lower end of the column 42 is provided with an encircling annular band 46 shown

in Figure 6, which is fitted over the end of the column.

The internal bore of the lower end of the column 42 is provided with splines 47, shown more clearly in Figure 4, which are adapted to mesh with co-operating splines 48 formed on a sleeve 49 which is 5 slidable along and concentric with the supporting column 12. A bracket 51, by means indicated at 53, is secured to the side wall of the washing machine vat shown in the dotted lines and identified by the numeral 52. The bracket 51 has a vertically extending slot 54 in which is 10 movable a fingerpiece 56 integral with the sleeve 49. A spring 57, one end of which butts against the lower end of the sleeve and the other end of which butts against a shoulder 58, formed internally of the bracket, urges the sleeve in an upward direction so that the splines 47 and 48 are normally in mesh. Internally of the bore in the bracket 51, as shown more clearly in Figure 5, 20 are splines 59 which engage with the splines 48 of the sleeve 49. An annular ring 61 is fitted over the upper end of the bracket 51 and serves to limit the upward movement of the sleeve 49, a stop 62 integral with the sleeve being normally 25 in engagement with the annular ring 61.

Normally, the wringer assembly is locked in position by engagement of the splines 47, 48 and 30 59. When the operator desires to shift the position of the wringer assembly, the fingerpiece 56 is depressed against the action of the spring 57 until the splines 48 are withdrawn from engagement with the splines 47, after which the entire wringer assembly may be freely rotated about the supporting column 12 as an axis. When the wringer assembly has been shifted to its desired position, the fingerpiece 56 is released and the spring 57 will push the sleeve 49 upward so as to re-engage the splines 48 with the splines 47, in which condition the wringer assembly is locked in position. 40

It will be apparent that I have provided a novel clam shell casing unit for the driving and reversing mechanism of the clothes wringer, in which the mechanism may be readily assembled, and have provided simple and easily operable means 45 whereby the wringer unit may be swung about a vertical axis and locked in the desired position. It will further be apparent that various modifications may be made in the form and relation of the parts without departing from the spirit of my invention as set forth in the appended claims.

I claim:

1. In a clothes wringer for a washing machine, a casing for housing the driving and reversing mechanism of the wringer, said casing having a 55 depending column having the lower end of the internal bore thereof splined, a supporting bracket having splines corresponding to the splines on the column, a splined element adapted to engage the splines on the column and the splines on the 60 bracket to retain the wringer assembly in a fixed position, and means enabling the splined element to be moved to disengage the splines thereof from one of said sets of splines to thereby enable the wringer to be swung about a vertical axis to a 65 desired position, said splined element being movable back into its normal position to lock the wringer assembly in its re-located position.

2. In a clothes wringer, a gear casing for housing the driving and reversing mechanism of the 70 wringer rolls, a column depending from the gear casing, a supporting tube extending upward internally of said column and adapted to support the wringer assembly, a set of splines located on the lower end of said column, a bracket adapted 75

to be supported from the vat of a washing machine located beneath said column and encircling said supporting tube, a set of splines located in the upper end of said bracket, means for locking said two sets of splines together comprising an element lying between said sets of splines and adapted to engage them, a spring normally adapted to move said element so that said sets of splines are locked

relative to each other, and means for moving said element against the action of said spring to disengage said element from one of said sets of splines so that the wringer assembly may be swung about said supporting tube into any one of a plurality of desired positions.

THOMAS J. LITTLE, JR.
